UNITED STATES PATENT OFFICE

156,087

DESIGN FOR A FISH FLOAT

Harry E. Fortune, Kansas City, Mo.

Application January 22, 1949, Serial No. 388

Term of patent 14 years

(Cl. D31—4)

To all whom it may concern:

Be it known that I, Harry E. Fortune, a citizen of the United States, residing at Kansas City, in the county of Jackson and State of Missouri, have invented a new, original, and ornamental Design for a Fish Float, of which the following is a specification, reference being had to the accompanying drawing, forming part thereof.

Fig. 1 is a side elevational view;

Fig. 2 is a top plan view; and

Fig. 3 is a bottom view of a fish float, showing my new design.

I claim:

The ornamental design for a fish float, as shown.

HARRY E. FORTUNE.
